ATTORNEY.

UNITED STATES PATENT OFFICE.

WELLINGTON B. SULLIVAN, OF BALTIMORE, MARYLAND.

CONTACT-SHOE.

1,385,100.

Specification of Letters Patent. Patented July 19, 1921.

Application filed October 25, 1919. Serial No. 333,391.

To all whom it may concern:

Be it known that I, WELLINGTON B. SULLIVAN, a citizen of the United States, residing at Baltimore city, State of Maryland, 5 have invented certain new and useful Improvements in Contact-Shoes, of which the following is a specification.

This invention relates to collectors for transmitting electrical energy to vehicles or 10 other moving objects, and more particularly to a current collector of that type embodying a shoe which slidably engages an electrically charged rail or similar conductor.

The invention has for its object to provide 15 the contact shoe with a novel and improved support, by which the shoe is held so that it readily adapts itself to irregularities in the conductor rail, the shoe being securely held in contact with the rail but at the same time 20 being free to yield in various directions to follow the rail.

The object stated is attained by means of a combination and arrangement of parts to be hereinafter described in detail, and while 25 the preferred embodiment of the invention has been disclosed, it will be understood that various changes and modifications may be made without a departure from the spirit and scope of the invention as claimed herein- 30 after.

In order that the invention may be better understood, reference is had to the accompanying drawing forming a part of this specification, and in said drawing,

35 Figure 1 is an elevation of the invention showing its application;

Fig. 2 is an enlarged side elevation of the invention, partly in section;

Fig. 3 is a front elevation, and

40 Fig. 4 is a horizontal section on the line 4—4 of Fig. 2.

Referring specifically to the drawing, 5 denotes a conductor rail carried by a suitable support 6 in a conduit 7. A slot 8 leads 45 from the surface of the ground down into the conduit, and the current collecting device enters the conduit through this slot. A fragment of the appliance to which the current taken from the electrically charged rail 50 5 is to be transmitted, is shown at 9. The invention is shown in connection with an under-ground conductor rail, but it will be understood that it is not limited thereto, but may, with equal facility, be used with conductors in different locations.

The current collecting shoe is a flat plate

10 engaging the under side or base of the rail 5. This plate seats on a pair of laterally spaced horizontal bracket arms 11.

The bracket arms 11 are supported by a 60 pair of laterally spaced and vertically positioned rods or bars 12 supported in guides 13 carried by a vertical bar 14 depending from the appliance 9. The rods 12 are free to slide in the guides 13 and at their upper 65 ends, they are connected by a cross bar 15.

Above the cross bar 15, the supporting bar 14 has vertically spaced guides 16 in which is slidably mounted a vertically positioned rod 17 connected at its lower end to 70 the cross bar 15 intermediate the ends of the latter.

Around the rod 17 is coiled a spring 18 which seats at its lower end on the bottom guide 16, and bears at its upper end against 75 an abutment 19. This spring tends to urge the rod 17 upwardly and the shoe 10 is therefore yieldingly held in contact with the bottom of the rail 5. The abutment 19 may be a washer which is held in place on 80 the rod 17 by a cross pin 20, the rod having a series of holes 21 for the pin so that the washer may be adjusted up or down on the rod to vary the tension of the spring 18.

On the bottom of the shoe 10 are transverse slots 22 in which the bracket arms 11 seat, and in the top of the latter are depressions to seat the semi-spherical heads 23 of screws 24 threaded through the shoe, the heads being at the bottom to seat in the depressions. It will be noted that the bracket arms 11 are spaced slightly at the top from the bottom of the shoe, this being for the purpose of permitting the latter to rock and follow irregularities in the rail 5. The 90 rocking movement is laterally or about an axis coinciding with a line drawn parallel to the rail 5 and intersecting the centers of the heads 23.

Each bracket arm 11 is integral with and 100 extends laterally from a clamping member 25, with which latter is associated a complementary clamping member 26. These two members are mounted on the rod 12, to which latter they are clamped by bolts 27, 105 with sleeves 28 of insulating material in the portions of the members encircling the rod.

A flexible conductor 29 is connected to the shoe 10 for transmitting the electric current to the apparatus on the appliance 9.

The shoe 10, in addition to its yielding contact with the rail 5, and its freedom to

tilt laterally, is also free to tilt in the direction of the length of the rail. The last described action results from the mounting of the rods 12. These rods are vertically 5 slidable and they are pivotally connected to the ends of the cross bar 15, as shown at 30, whereas the rod 17 is pivotally connected to said cross bar, as shown at 31. These pivot joints are sufficiently loose to permit 10 a slight up and down play of the rods 12 in opposite directions, the cross bar 15 rocking on the pivot 31.

I claim:

1. A current collector comprising a contact shoe, and a support for the shoe, including bracket arms extending beneath the shoe, the bottom of the shoe having semi-spherical protuberances, and the top of the bracket arms having recesses in which the 20 protuberances seat, and the opposite surfaces of the shoe and the bracket arms being spaced.

2. A current collector comprising a contact shoe, and a support for the shoe, including bracket arms extending beneath the shoe, the bottom of the latter being recessed to seat the bracket arms, and said recessed portion of the shoe having semi-spherical protuberances and the top of the bracket 30 arms having recesses in which the protuberances seat, the opposite surfaces of the shoe and the bracket arms being spaced.

3. A current collector comprising a contact shoe, bracket arms supporting the shoe, 35 slidable supports for the bracket arms, a cross-connection between the supports, said connection being loose to permit the supports to slide in opposite directions, and a slidable member loosely connected to the 40 cross-connection.

4. A current collector comprising a contact shoe, bracket arms supporting the shoe, slidable supports for the bracket arms, a cross-connection between the supports, said 45 connection being loose to permit the supports to slide in opposite directions, a slidable member loosely connected to the cross-connection, and a spring associated with said member for yieldingly urging the same in 50 one direction.

5. A current collector comprising a contact shoe, bracket arms extending beneath the shoe, the bottom of the shoe having semi-spherical protuberances, and the top of the 55 bracket arms having recesses in which the protuberances seat, and the opposite surfaces of the shoe and the bracket arms being

spaced, slidable supports for the bracket arms, a cross-connection between the supports, said connection being loose to permit 60 the supports to slide in opposite directions, and a slidable member loosely connected to the cross-connection.

6. A current collector comprising a contact shoe, bracket arms extending beneath the shoe, the bottom of the shoe having semi-spherical protuberances, and the top of the bracket arms having recesses in which the protuberances seat, and the opposite surfaces of the shoe and the bracket arms being 70 spaced, slidable supports for the bracket arms, a cross-connection between the supports, said connection being loose to permit the supports to slide in opposite directions, a slidable member loosely connected to the 75 cross-connection, and a spring associated with the said member for yieldingly urging the same in one direction.

7. A current collector comprising a contact shoe adapted to run on a current conductor, and means for supporting the shoe to normally permit the same to tilt laterally and in the direction of the length of the current conductor.

8. A current collector comprising a contact shoe adapted to run on a current conductor, means for supporting the shoe to normally permit the same to tilt laterally and in the direction of the length of the current conductor, and a slidable support 90 for said means.

9. A current collector comprising a contact shoe adapted to run on a current conductor, bracket arms supporting the shoe, 95 slidable supports for the bracket arms from which the latter are insulated, a loose cross connection between the supports, and a slidable member connected to the cross connection.

10. A current collector comprising a contact shoe adapted to run on a current conductor, bracket arms supporting the shoe, slidable supports for the bracket arms to which the latter are detachably connected, a loose cross connection between the supports, and a slidable member connected to the cross connection.

In testimony whereof I affix my signature in the presence of two witnesses.

WELLINGTON B. SULLIVAN.
